ABSTRACT OF THE DISCLOSURE

A cooling unit for use with a refrigeration system, such unit being composed of one or more upright open ended bodies each of generally straight sleeves of different diameters arranged in concentric relation about a common axis, said sleeves having their end portions arranged in gradually converging relation and providing closed annular refrigerant chambers with inner and outer exposed surfaces constituting refrigerating surfaces which decrease gradually in proximity to each other toward the ends of the unit and with the extremities of each open ended body unrestricted and minimizing excessive build-up of refrigerated product which would interfere with the release of the product from the cooling unit.

CROSS-REFERENCE TO RELATED APPLICATION

This application is a continuation-in-part of my co-pending application Ser. No. 665,784, filed Sept. 6, 1967.

BACKGROUND OF THE INVENTION

Field of the invention

The invention relates to refrigeration and particularly to the cooling unit of a refrigeration system consisting of one or more elements for producing ice in small particles.

Description of the prior art

Prior art devices have produced ice on the surfaces of cylinders; however, these have been complicated, expensive, inefficient, unreliable, as well as of limited capacity and excessive weight, and required skilled attendants for their use and maintenance.

SUMMARY OF THE INVENTION

A cooling unit of multiple elements each composed of opened ended concentric cylinders in upright position with the ends of the concentric cylinders merged together in gradually converging relation about a common axis and providing an annular refrigerant chamber. The remote inner and outer exposed surfaces of the cylinders constitute refrigerating surfaces decreasing gradually in proximity to each other toward the ends of the elements and with the extremities of each refrigerating element unrestricted thereby minimizing excessive build-up of the refrigerated product which would interfere with the release of the product from the unit. The multiple elements connected in series are particularly useful in an area where height is restricted, it being understood that the operation of supplying the heat to the cooling unit to facilitate release of the product therefrom is controlled alternately of the refrigerating cycles.

It is an object of the invention to provide a simple, practical, relatively inexpensive, highly efficient and reliable cooling unit for the freezing of water to produce ice or for the refrigeration of other matter, although it will be apparent that the unit may be employed for effecting heat exchange and, therefore, for heating as well as cooling.

2

Another object of the invention is to provide a cooling unit of the character indicated having means by which the interior and exterior refrigerating surfaces can have their temperature quickly modified by heat from another part of the refrigeration system causing the release of ice or other products treated and desired to be harvested therefrom.

Another object of the invention is to provide a cooling unit consisting of a pair of sleeves one within the other, merged together and connected at their ends to provide a refrigerant chamber between the sleeves and with the interior and exterior surfaces serving to produce a refrigerating effect.

A further object of the invention is to provide a simple, practical, relatively inexpensive, highly efficient and reliable cooling unit of relatively small cylinders and low profile, particularly useful where height is restricted, for the refrigeration of water or other product, as well as to employ the unit as a heat exchanger for heating as well as cooling.

Other objects and advantages of the invention will be apparent from the following description considered in conjunction with the accompanying drawings.

BRIEF DESCRIPTION OF THE DRAWINGS

FIG. 1 is a diagrammatic view illustrating one application of the invention;

FIG. 2, a top plan view of the cooling unit;

FIG. 3, a vertical section of the cooling unit and illustrating in detail the manner in which the refrigerant is supplied and removed;

FIG. 4, a fragmentary enlarged detail view of the merging and joining of the concentric cylinders;

FIG. 5, a fragmentary view of a modified form with a capillary tube;

FIG. 6, a top plan view illustrating a simple refrigerating unit of two elements with common supply and return lines instead of merely a single element as disclosed in FIGS. 1-5;

FIG. 7, a diagrammatic view illustrating a refrigeration system employing the cooling unit of FIG. 6 with the latter illustrated in longitudinal section;

FIG. 8, a vertical section on the line 8—8 of FIG. 7;

FIG. 9, a horizontal section on the line 9—9 of FIG. 7;

FIG. 10, a top plan view of a multiple cooling unit employing four cooling elements;

FIG. 11, a diagrammatic view of a refrigeration system incorporating the cooling unit of FIG. 10 with the latter illustrated in vertical section;

FIG. 12, a fragmentary view in larger detail of the merging and joining of the concentric cylinders on the vertical line 12—12 of FIG. 11; and

FIG. 13, a similarly enlarged vertical section illustrating the connection between two of the contiguous cylinders.

DESCRIPTION OF THE PREFERRED EMBODIMENTS

With continued reference to the drawings, a cooling unit 10 is provided composed of internal and external sleeves or cylinders 11 and 12 of different diameters arranged in concentric relation about a common axis and merged together at their extremities to provide upper and lower closed ends 13 and 14. The merging of the two concentric sleeves or cylinders is in gradually converging relation providing a closed annular refrigerant chamber with the remote inner and outer surfaces of the sleeves constituting the refrigerating surfaces which decrease gradually in proximity to each other toward the top and bottom of the same and with the extremities of the open ended body unrestricted. The connection of the sleeves or cylinders may be done in any desired manner, as for

example by providing the inner sleeves or cylinders 11 with flared extremities 15 and 16 and brazing, soldering or otherwise fusing them to the extremities of the external cylinders 12.

When these cylinders or sleeves 11 and 12 are connected they provide an annular refrigerant chamber 17 and the inner surface 18 of the inner cylinder or sleeve 11, and the outer surface 19 of the outer cylinder or sleeve 12, form refrigerating or temperature modifying areas subject to the refrigerant or heat exchange medium within the chamber 17. In view of the fact that the cooling unit is in the form of an open ended or unrestricted body excessive build-up of refrigerated product which would interfere with the release of the product from the unit is minimized. On these interior and exterior surfaces water or other substance may be applied in any desired manner, as for example by means of a spray head 20 on the interior and a spray ring 21 about the exterior of the cooling unit and with such spray head and spray ring supplied from a water line 22. The spray ring 21 may be mounted by means of a series of supporting straps 23, while the spray head 20 may be supported in any desired manner. Water or other substance applied to the internal and external refrigerating surfaces of the cooling unit will be refrigerated or subjected to heat modification in accordance with the fluid within the chamber 17.

In order to provide for a refrigerating effect the cooling unit may form part of a conventional refrigeration system with a refrigerant or gas line 26 extending downwardly between the two cylinders and having a lower end 27 terminating near the bottom of the refrigerant chamber, thus allowing the gas to expand within the chamber and flow upwardly between the outer and inner walls and the gas to be removed near the top through a return line 27' which will recycle the gas through the compressor so that it can be cooled and liquefied. The liquid refrigerant then passes through a conventional expansion valve 28, capillary tube, or other differential maintaining element, between the high and low pressure sides of the system.

In order to harvest the refrigerated product or release it, a line 29 may be provided in communication with the compressor 24 and joined with the line 26 beyond the expansion valve 28 and subject to a valve 30 under the control of a solenoid and timer 31. When the valve 30 is open compressed hot gas from the compressor will be admitted from the line 26 into the refrigerant chamber 17 to heat and release the refrigerated product and the operation of the timer is synchronized so that it operates between refrigeration cycles. An expansion valve is employed in FIG. 1, while in FIG. 5 a capillary tube 29' is utilized, otherwise the parts are substantially the same in these two figures and the refrigeration systems operate in a similar manner. The unit may have attached thereto an upwardly extending threaded stud 32 extending through and attached to a mounting plate 33 by means of nuts 34.

As illustrated in FIGS. 6-13, inclusive, the cooling unit may be composed of a series of cooling elements 10, each as in FIGS. 1-5, composed of internal and external cylinders or sleeves 11 and 12 of different diameters arranged in concentric relation about a common axis and merged together and connected at their extremities to provide upper and lower closed ends 13 and 14, the merging of the two concentric sleeves or cylinders of each element in gradually converging relation as in the preceding figures but providing the inner sleeves or cylinders 11 with upper and lower flared extremities 15 and 16 and brazing, soldering or otherwise fusing them to the extremities of the external cylinders 12. As previously described, an annular refrigerant chamber 17 is provided between each pair of sleeves or cylinders and the inner surface 18 of the inner cylinder or sleeve 11 and the outer surface 19 of the outer cylinder or sleeve 12 form re-

frigerating or temperature modifying areas subject to the refrigerant or heat exchange medium within the chamber 17.

5 A spray head 20 on the interior and an oval spray ring 35 on the exterior of the cooling unit having spray nozzles 36, 37 and 38 of different lengths and with such spray ring supplied from a water line 39. The spray ring 35 may be supported by a series of straps 23 while the spray head 20 may be supported in any convenient or desired manner.

10 Water or other substance, the temperature of which is to be modified, may be supplied to the internal and external surfaces 18 and 19 of the cooling unit for refrigeration or temperature modification in accordance with the fluid within the chambers 17. The elements which comprise the cooling unit may have peripheral proportions in contact as illustrated in FIGS. 6 and 10 in which event the refrigerating chambers, connected in series by means of communicating openings 40 and as 15 in FIGS. 1-5, may be formed as part of a refrigeration system including a compressor 41, condenser 42, and a liquid line 43 and expansion valve 44 from which the refrigerant is supplied through line 45 into the upper end of the refrigerating chamber 17 from which it can flow through the opening 40 into the next successive 20 temperature modification element, and the gas removed through the return line 46 and returned to the compressor 41. Hot compressed gas from the compressor likewise may be allowed to flow through a line 47 and through a valve 48 subject to a timer 31.

25 Instead of a pair of cooling elements, as illustrated in FIGS. 6 and 7, additional cooling elements may be employed as illustrated in FIGS. 10 and 11 wherein the compressor 50 discharges hot compressed refrigerant 30 through a line 51 to a condenser 52 from which condensed refrigerant may flow through a line 53 to an expansion valve 54 and through a line 55 into the first of the series 35 of cooling elements and through openings 40 and 56 40 through the several elements in series, after which the gas is returned through a suction line 57 to the compressor 50. A line 58 connects the refrigerant line 51 from the compressor to the line 55 to the cooling units and is subject to a valve 59 controlled by the timer 31 to cause hot 45 gas to flow into the cooling elements and cause release of the congealed product therefrom. Water is supplied through nozzles 20 to the interior and exterior of the refrigerating elements by means of an oval spray ring 60 mounted by brackets 23. The nozzles 20 and the spray rings 21, 35 and 60 are supplied with water from any 50 desired source.

55 It will be apparent that a simple, practical refrigerating unit is provided which may be of one, two, four, or any desired number of cooling elements and where height is limited the desired refrigerating effect can be obtained with multiple units.

It will be obvious to one skilled in the art that various changes may be made in the described embodiments of the invention without departing from the spirit and scope thereof and therefore the invention is not limited by that which is illustrated in the drawings and described in the specification, but only as indicated in the accompanying claims.

I claim:

1. An apparatus for reducing temperature a refrigeration system including a cooling unit having an upright open ended body of generally straight sleeves of different diameters arranged in concentric relation about a common axis, said sleeves having their end portions merged together in gradually converging relation and providing 60 a closed annular refrigerant chamber with the remote inner and outer exposed surfaces of said sleeves constituting refrigerating surfaces which decrease gradually in proximity to each other towards the ends of said unit and with the extremities of said open ended body unrestricted and thereby minimizing excessive build-up of refrigerated

product which would interfere with the release of such product from the interior and exterior surfaces of said body, means whereby refrigerant may be supplied to and removed from said refrigerant chamber, and means for supplying matter to be refrigerated to the interior and exterior surfaces of said unit.

2. The structure of claim 1 in which the means whereby refrigerant may be supplied is near the bottom of the refrigerant chamber.

3. The structure of claim 1 and means for supplying heat to said cooling unit to facilitate release of the refrigerated product therefrom.

4. The structure of claim 1 in which the means by which refrigerant may be admitted is near the bottom of the refrigerant chamber, and with means for supplying heat to said refrigerant chamber near the bottom thereof and around the area of admission of the refrigerant to facilitate release of the refrigerated product from the inner and outer exterior surfaces of said cooling unit.

5. The structure of claim 1, and means for supplying heat to said cooling unit to facilitate release of the refrigerated product therefrom, and means for controlling the application of heat alternately between refrigerating cycles of said cooling unit.

6. The structure of claim 1 and detachable mechanical means for suspending said unit from a support.

7. The structure of claim 1 in which the outer concentric sleeve is generally straight and the inner concentric sleeve has its ends gradually expanded into contact with the outer concentric sleeve.

8. A cooling unit for a refrigeration system comprising a series of individual cooling elements each composed of upright open ended bodies of generally straight sleeves of different diameters arranged in concentric relation about a common axis, the sleeves of each cooling ele- 35

ment having their end portions merged together in gradually converging relation and providing a closed annular refrigerant chamber with the remote inner and outer exposed surface of said sleeves constituting refrigerating surfaces which decrease gradually in proximity to each other towards the ends of said unit and with the extremities of said upright open ended body unrestricted and thereby minimizing excessive build-up of refrigerated product which would interfere with the release of such product from the interior and exterior surfaces of said body, means whereby refrigerant may be supplied to the first and removed from the last of the series of refrigeration elements, and means for supplying matter to be refrigerated to the interior and exterior surfaces of said cooling elements.

9. The structure of claim 8 in which the means for supplying matter to be refrigerated to the exterior surfaces of said unit includes unitary spray means extending about multiple individual cooling elements.

10. Apparatus comprising a series of cooling units of the character set forth in claim 1 connected in series and usable in an area where height is limited.
